(57) **CLAIM**

We claim the ornamental design for a transformable glove, as shown and described.

DESCRIPTION

FIGS. 1-6 are views of a transformable glove shown with a finger pocket in an enclosed position, showing our new design.

FIG. 1 is a front elevation view of the transformable glove. FIG. 2 is a back elevation view of the transformable glove. FIG. 3 is a left side elevation view of the transformable glove. FIG. 4 is a right side elevation view of the transformable glove.

FIG. 5 is a top plan view of the transformable glove. FIG. 6 is a bottom plan view of the transformable glove. FIGS. 7-12 are views of the transformable glove of FIGS. 1-6, shown with the finger pocket folded back in an open position. FIG. 7 is a front elevation view of the transformable glove. FIG. 8 is a right side elevation view of the transformable glove.

FIG. 9 is a top plan view of the transformable glove. FIG. 10 is a right side view of the transformable glove; FIG. 11 is a top view of the transformable glove; and, FIG. 12 is a bottom plan view of the transformable glove. Features illustrated in phantom lines are intended to show a preferred environment for the transformable glove and form no part of claimed invention. Aspects illustrated in phantom lines include zipper and zipper pull, reflective appliqué on finger pocket as best seen in front view of FIG. 1 in upper portion of figure; zig-zag stitching as best seen in the front view of FIG. 1, the back view of FIG. 2, the front view of FIG. 7, and the back view of FIG. 8, and a fastening stitch partially overlapping central zig-zag stitch as best seen in FIG. 8.
